UNITED STATES PATENT OFFICE.

OLAF HETLESATER, OF SEATTLE, WASHINGTON; ELISABETH HETLESATER EXECUTRIX
OF SAID OLAF HETLESATER, DECEASED.

EXCAVATING MACHINE.

Application filed March 10, 1926. Serial No. 83,754.

My invention relates to excavators for road building and irrigation ditches in which a single excavating bucket operates in conjunction with side pockets located on 5 and part of the excavator for digging and transporting the excavated material to the dump; and my objects are, first, to eliminate teams or trucks for transporting the excavated material; second, to provide a light, 10 easily propelled machine, and, third, powerful enough to dig ordinary material without previous plowing.

These objects, and others which will appear later, I attain by the mechanism illustrated in the accompanying drawings, in which Fig. 1 is a side elevation of the machine with one side pocket and one set of rear wheels removed; Fig. 2, a partial plan view; Fig. 3, a partial vertical section on 20 broken line 3-3; Fig. 4, a vertical section of gear housing and supports on broken line 4-4; Fig. 5, a horizontal section on broken line 5-5 of gear housing and support; Fig. 25 6, a plan view of suspension links; Fig. 7, a partial side view of gear housing and dipper handle with lip adjusting rod in its dumping position, showing crank and suspension arm with shock spring housing; Fig. 8, view of suspension arm and pin for lip adjusting 30 rod; Fig. 9, plan sectional view of swinging crank and anchors on broken line 9-9; Fig. 10, developed surface of worm for actuating the swinging crank. Similar figures refer to similar parts throughout the several 35 views.

To a tractor 1, is secured a frame 2, 2¹ and 2², preferably built in sections with a column 3, and a tie rod 4; a top frame 5, is secured to top of frame 2², supporting a 40 hopper support 6, with a bearing 7. To frame 2¹, with cap 8 is formed a step bearing 8¹, for worm housing 9, which at its upper end is provided with trunnion 9¹, rotatively held by a cap 10, forming a bearing 45 in said frame 2² in which said worm housing is free to revolve. To said worm housing is bolted two trunnions, 11 and 11¹, which supports an upper gear housing 12, provided with trunnion bearings 13 and 13¹, and caps 14, forming a pivot for said gear housing, which on top has two suspension lugs 15, and 15¹; a pin 16 and U straps 17 and 18, which with spring bolt 19 and spring 20 forms the spring suspension link. A pin 55 21 secures said U strap 18 to suspension nut

22, which is adjusted and supported by screw 23, upper end of which is held by said bearing 7 and lower end by a step bearing 24, formed in said top frame 5. To the lower end of said screw 23 is keyed a worm 60 wheel 25, engaging with a worm 26, which is keyed to shaft 27, turning in bearings 28 and 28¹, formed in said top frame 5; a hand wheel 29 is keyed to the outer end of said shaft 27, by which said suspension nut 65 22 is adjusted in a vertical plane. Integral with said upper gear housing 12 and with bearings 13 and 13¹, is cast bearings 30-30¹, and 30², and also bearing 31; said bearings, 30 and 31, are provided with caps 32 and 33 70 respectively. Said bearings 30, 30¹ and 30², forms the supports for crank shaft 34, to which is keyed cranks 35 and 35¹, having at their outer end crank pins 36 and 36¹.

Motion is taken from tractor worm shaft 75 37 by slip coupling 38, operated by hand lever 39 and keyed to shaft 40, to the outer end of which is keyed a bevel gear 41, supported in ball bearing 42 and engaging with bevel gear 43, keyed to a worm 44 and guided by ball bearing 45. The upper end of said worm is provided with a double thrust bearing 46; through nut 47 collar 48, follower 49, thrust is transmitted to said frame 2², and said worm housing 9, in which said thrust bearing 46 is held. The lower end of said worm housing 9 transmits thrust to said frame 2, and forms the housing for said ball bearing 45. The upper end of said worm 44 is held in ball bearing 50, formed in said 80 frame 2¹. A fly wheel 51 is keyed to the upper end of said worm 44. A shaft 52 having concentric bearings in said trunnions 11 and 11¹, has a worm wheel 53 keyed between said bearings and an elliptic gear 54 85 keyed at one end. Said worm wheel 53 meshes with said worm 44. Meshing with said elliptic gear 54 and keyed to said shaft 34 is another elliptic gear 54¹, which transmits a variable speed to said shaft 34 and 90 to said crank pins 36 and 36¹, centrally on said crank shaft 34 is keyed a worm 55, the developed thread 55¹, shown in Fig. 10 is formed with a straight interval 55², thus transmitting an interrupted motion to worm 105 wheel 56, which is keyed to swinging shaft 57, upper end of which is held in said bearing 31; the lower end is supported by bearing 58 formed in lower gear housing 59, and has keyed on a swinging crank 60, provided 110

with an eye bolt 61 at its outer end. Two anchor rods 62 and 62¹, link in said eye bolt 61 and is provided at their outer ends with two spring washers 63 63¹ and two nuts 64, and 64¹ respectively. Two anchor springs 65 and 65¹ transmit the pull from said anchor rods 62 and 62¹, to eye bolts 66 and 66¹ in holes 67 provided in swinging anchor frame 68, in which they are free to turn. Said anchor frame is bolted to said frame 2¹. Said lower gear housing 59 is cast partly open in the bottom and at one end to afford clearance for swinging and lowering. Integral with it is cast bearing caps 69 and 69¹, and also two lugs 70 and 70¹, from which a forward support 71 is suspended by pin 72. The said upper gear housing 12 is at the top inner end provided with two shoulder lugs 73 and 73¹, from which through pins 74 and 74¹ 20 suspension arms 75 are hung, the lower end of which by pins 76 connects with handle 77 and 77¹. At a suitable intermediate position on said suspension arm 75 is located a pin 78 for connection with lip adjusting rods 79 and 79¹. Said suspension arm 75 is preferably made double with a space between for clearance for said handles 77 and 77¹; a sliding block 80 is arranged to work in a slot 80¹ in said handle 77 together with 30 shock springs 81 and is also arranged to receive said crank pins 36 and 36¹. Said handle 77 is cast hollow to receive dipper handles proper 82 and 82¹ which are secured to same. At the outer ends of said dipper handles and secured to same are dipper pivots 83 and 83¹, from which through pin 84 dipper 85 is suspended, at the lower and outer end of which the dipper lip 86 is articulately attached through pin 87, said 40 dipper lip 86 being provided with teeth 88, and at the upper ends with pins 89 and 89¹, connecting with lip adjusting rods 79 and 79¹; at the lower end and on the sides of said dipper 85 is fastened lugs 90 which through pins 91 attaches to spring rods 92. These rods through suitable apertures in 45 said dipper pivots 83 and 83¹, engages with cushion springs 93 and 93¹.

To said hopper support 6 is secured a hopper 94, provided with side chutes 95 and 95¹, and with back stop 96 and also braces 97 and 97¹.

Machine is supported on dead axle 98 clamped to said frame 2 by clamps 99 and 99¹ and provided with trunnions on the outer ends, on which wheels 100 turn, to the rims of which another pair of wheels 101 are bolted; said wheels centered and secured on axles 102, on which is supported a side pocket 103 by supports 104 and 105; between said supports and on said axle 102 is located wheel 106. At the rear end of said side pocket 103 and supported by said supports 104 and 105 is axle 107; between said supports and on said axle is located counter

balance wheel 108. On one side of side pocket 103 in a convenient location is riveted stop angle 109, arranged to engage stop 110, which is keyed to shaft 111, supported in bearings 112, which are secured to said hopper support 6. Said shaft 111 is provided with a hand lever 113, located in a convenient position.

To said wheels 100 is secured a gear 114 and a sprocket 115, arranged to mesh with pinion 116 and through a sprocket chain 117 with sprocket 118, which respectively are provided with friction clutch members 119 and 119¹, arranged to be selectively driven by another clutch member 120, keyed to original drive axle of tractor and operated by clutch lever 121, conveniently pivoted on said frame 2.

The operation of my machine is as follows:

Through one revolution of the cranks 36 and 36¹, the dipper 85 is moved on path *d—d—d* in direction of the arrows; due to the inner end of handles 82 and 82¹, being attached to and guided by the suspension arms 75 and 75¹, which will swing in an arch from shoulder lugs 73 and 73¹. The elliptic gear 54 is keyed on the shaft 34 in such relation to cranks 36 and 36¹ that the slow motion of the dipper will occur at the lower part of path *d—d—d*, where great power is required, and the fast motion at the upper part of path *d—d—d*, where great speed is desirable, to throw the material into the hopper.

By the adjusting rods 77 the dipper lip is at the lower part of the path adjusted in regard to the bank so as to procure a better digging angle than if the dipper lip were rigidly connected to the dipper, and at the upper end of the path the lip opens up and frees the material at the time of delivery. Due to the speed of the dipper at the top of path, it is reluctant to stop immediately, which also would produce great shock and strain on the parts. To absorb this stored up energy, dipper and its load is allowed to rise and swing around pivot pin 84 at its upper end and is gradually retarded in this motion by cushion springs 93 and 93¹. It thus follows path *e—e—e* and springs 93 and 93¹ are adjusted to just give it a slight shock at the top to release clay or sticky material more easily.

Due to the relative position of the cranks 36 and suspension arms 75, at the time dipper should start on its down path shock springs 81 and sliding block 80 will allow cranks to continue their motion by compressing the spring 81, which limits the force exerted on the dipper tending to increase its acceleration over that produced by gravity, until such time and position in the return path of the dipper when speed has been reduced to conform with the speed gravity naturally would give to the falling bucket. The spring 81 will then re-

turn block 80 to its normal position, and the gradually retarded motion of the dipper will absorb the momentum of the fall. To regulate the speed of the machine and augment the force available while dipper is forced through the bank, a fly wheel is arranged at the top of worm 44 as shown.

The swinging of the dipper and gear housing is accomplished by worm 55, wheel 56 and crank 60, so that for one revolution of worm dipper will have swung only an amount equal to its width and the total number of side swings to be able to dig a swath wide enough to afford passage off the machine in the bottom of the cut. Alternately the material dug will be thrown along projectory $t-t$ or t^1-t^1 according to speed into each side pocket; the center loads will be dumped in center of hopper where the first few dipper loads will remain, forming a cushion and a slope for the following center loads. When both side pockets are filled, machine is stopped by throwing out clutch 38 after previous slowing down of the tractor engine, leaving the dipper and handle in top position. Machine is fed into the bank by hand lever at the judgement of the operator. The sliding back of the machine when dipper is forced into the bank is prevented by suitable blocks back of the rear wheels. The side pockets when loaded has an over balancing effect forward from the axis of rear wheels and the stop 109 on the side is located so that, in hard surface, wheels 108 will be a couple inches off from the ground, but will in soft ground carry a small part of the load in proportion to their surface and depth of sinking in. Machine is now propelled to the dump until the forward wheels of the tractor is on the edge of the dump. Side pockets are now released by hand lever 113 and swings forward and down to position D, and material slides onto and over the edge of the dump, wheels 108 being lifted up as shown in dotted lines. When all material is out, the weight of the wheels 108 will overbalance the empty side pocket and it will return to its former position with wheels 108 on the ground and stop 109 is returned to its locking position and locked by the hand lever 113. Machine is now propelled back to the digging place.

Although I have shown the machine as it would preferably be constructed for road building, it can be arranged for excavating irrigation ditches by substituting belt conveyors on each side for overcasting the excavated material to both sides beyond the berme, and the machine proper would be as shown. The drive for these conveyors could be taken from the pulley on the side of the tractor, or, if greater capacity was desired, from an independent motor located on the frame work of the conveyor, which would be supported on the rear wheel axles in a

similar manner as the side pockets are shown. I thus do not limit myself to the precise arrangement shown, but any other arrangement, without materially changing the machine, within the scope of my invention, can be used.

I am aware that prior to my invention excavating machines, such as scrapers, have been in use digging the material and transporting it propelled by horses or tractors to the dump. Therefore I do not claim such a combination broadly, but

What I do claim as my invention and desire to secure by Letters Patent is:

1. The combination of an excavator, a tractor, two side pockets rotatively supported on axles having a common center with rear axle of said tractor, a pair of wheels on each of said axles, a supplementary axle on each of said side pockets, a locking device on said tractor, and a balancing wheel on each of said supplementary axles.

2. The combination of an excavator, and a tractor, having two side pockets rotatively supported on axles and wheels, a supplementary axle with balancing wheel on one end of each of said side pockets, other end to be open for dumping, and a locking and unlocking device for said side pockets located on said tractor substantially as specified.

3. An excavator having a bucket with a hinge connection at the upper end and a spring connection at the lower end, a handle, hinge connected to said bucket, a spring anchored to said handle, means for imparting motion and direction to said bucket and said handle, the velocity and direction of said bucket and handle being such, as to discharge the bucket contents by energy stored therein, said spring absorbing the energy stored in said bucket, by allowing it to revolve about said hinge, thereby compressing said spring.

4. An excavator, having a bucket, a handle connected to said bucket in one end, other end being pin connected to an arm, an intermediate crank pin connection on said handle, means for imparting motion to said handle through said crank pin connection, and means for anchoring upper end of said arm.

5. In an excavator, the combination of a bucket, a handle connected to said bucket in one end, other end being pin connected to an arm, a sliding block intermediately housed on said handle, adapted to receive a crank pin, a spring housed back of said sliding block on said handle, arranged to allow said sliding block to compress said spring when motion of said crank pin so demands, means for imparting motion to said crank pin, and means for rotatively anchoring upper end of said arm.

6. In an excavator, the combination of a bucket, a hinged lip on said bucket, a handle

connected to said bucket, a lip adjusting rod connected to said hinged lip, an arm, one end of said arm being pin connected to said handle, other end being rotatively anchored, said 5 arm having an intermediate pin connection to said lip adjusting rod, and means for imparting motion to said handle.

7. In an excavator, the combination of a bucket with a link suspended and crank 10 actuated handle, a crank actuating said handle, a crank shaft keyed to said crank, a lay shaft, a pair of elliptic gears, with equal 15 number of teeth, keyed respectively to the said lay shaft and crank shaft, and meshing together, the uniformly revolving lay shaft thereby imparting a variable motion to the crank shaft, a worm wheel keyed to said lay shaft, means for supporting said crank shaft and lay shaft and means to transmit motion 20 to said worm wheel.

8. In an excavator, the combination of a bucket, a link suspended and crank operated handle, a crank actuating said handle, a crank actuating mechanism, a lay shaft, a 25 worm wheel keyed to said lay shaft, a housing for said worm wheel having a pair of trunnions in a vertical plane, and another pair of trunnions in a horizontal plane, forming 30 bearings for said lay shaft, a frame rotatively supported on said horizontal trunnions and forming housing and support for said crank actuating mechanism, a worm shaft concentric with said vertical trunnions, meshing with said worm wheel, means for 35 imparting motion to said worm shaft, means for suspending said frame, and bearings for supporting said vertical trunnions of said worm gear housing rotatively substantially as described.

9. In an excavator, the combination of a 40 bucket, a link suspended crank actuated handle, a crank actuating mechanism, a housing supporting said handle and forming a housing for said crank actuating mechanism, a worm gear housing rotatively supporting 45 said housing, allowing motion in a vertical plane, a frame rotatively supporting said worm gear housing, allowing motion in a horizontal plane, an elastic pin connected suspension link suspending said housing, a 50 vertically adjustable suspension nut, pin connected to upper end of said suspension link, a forward support suspended from forward end of said housing, acting in conjunction with said suspension link, and means for raising and lowering said suspension nut substantially as specified.

10. In an excavator, the combination of a bucket, a link suspended crank actuated handle, a crank shaft, a housing supporting said 60 crank shaft, a worm wheel housing supporting said housing, a body frame forming trunnion bearings for said worm wheel housing, a worm with a partially interrupted lead, 65 keyed onto said crank shaft, a worm wheel meshing with said worm, a swinging shaft, keyed to said worm wheel and held in bearings in said housing, a swinging crank keyed to the lower end of said swinging shaft, a 70 swinging anchor frame with two anchor arms and secured to said body frame, two anchor rods, two springs, connections for said anchor rods to said swinging crank and to said anchor frame, and means for imparting motion to said crank shaft substantially 75 as specified.

OLAF HETLESATER.
